United States Patent Office

Des. 211,694

Patented July 16, 1968

211,694

DOLL'S HEAD

Dianne S. Dengel, Rochester, N.Y., assignor of twelve and one-half percent to Winslow E. Thomson and twelve and one-half percent to John R. Schovée

Filed Aug. 9, 1965, Ser. No. 86,489

Term of patent 3½ years

(Cl. D34—4)

FIG. 1

FIG. 2

FIG. 3

FIG. 4

FIG. 1 is a front elevation of the doll's head showing my new design;

FIG. 2 is a perspective view thereof;

FIG. 3 is a perspective top view thereof;

FIG. 4 is a rear elevation thereof.

I claim:

The ornamental design for a doll's head, as shown.
